UNITED STATES PATENT OFFICE.

CHARLES M. RHODES, OF STEUBENVILLE, OHIO, ASSIGNOR TO THE RHODES MANUFACTURING COMPANY, OF STEUBENVILLE, OHIO, A CORPORATION OF OHIO.

WINDOW-SASH.

SPECIFICATION forming part of Letters Patent No. 775,858, dated November 22, 1904.

Application filed January 18, 1904. Serial No. 189,509. (No model.)

To all whom it may concern:

Be it known that I, CHARLES M. RHODES, a citizen of the United States of America, residing at Steubenville, in the county of Jefferson 5 and State of Ohio, have invented certain new and useful Improvements in Window-Sashes, of which the following is a specification, reference being had therein to the accompanying drawings.

10 This invention relates to certain new and useful improvements in window-sashes, and has for its object to provide novel means whereby a sash may be easily and quickly removed from its frame without removing the strips of 15 the frame or in any manner injuring the same.

A further object of my invention is to provide means carried by the frame and the sash whereby the sash may be readily swung from its position within the frame to facilitate the 20 cleaning of the glass when desired.

Briefly described, my improved sash comprises two sections which are secured together by any suitable means, whereby they may be readily operated as one sash, and in providing 25 these sections I cut away a portion of one side of the sash, this portion being adapted to remain in the frame, while the other portion is removed, at which time the cut-away portion may also be removed. On the other side of 30 the sash I provide hinge members which are adjustably mounted within the frame of the window and are adapted to engage the socket members carried by the sash, so the same may be readily swung outwardly from its position 35 in the frame of the window.

The invention further consists in the novel construction, combination, and arrangement of parts to be hereinafter more fully described, and specifically pointed out in the claims.

40 In describing the invention in detail reference is had to the accompanying drawings, forming a part of this application, and wherein like numerals of reference indicate like parts throughout the several views, in which—

45 Figure 1 is a view of a portion of a frame, showing my improved sash placed therein. Fig. 2 is a top plan view of one of the sashes. Fig. 3 is a horizontal sectional view of the same,

taken on the line 33 of Fig. 1. Fig. 4 is a fragmentary perspective view of the body portion of the sash. Fig. 5 is a perspective view of the detached member. Fig. 6 is a fragmentary sectional view of one side of the frame, showing the adjustable hinged member; and Fig. 7 is a detail perspective view 55 of the adjusting mechanism of this member.

I have herein illustrated my invention with a sash having racks 1 on the vertical rails thereof, these racks being adapted to ride in grooves provided therefor in the frame and 60 adapted also to be engaged by toothed wheels of an operating mechanism mounted in the frame, (not shown herein,) but of such a form as shown and described in my application filed February 26, 1903, Serial No. 145,268, the present invention being designed 65 particularly for use in connection with operating mechanism of the character stated.

The reference-numeral 2 indicates the body portion of the sash, and upon its one side is 70 cut away, as indicated at 3, this cut-away portion forming the detachable member, which is secured to the body portion of the frame by means of the screw-bolt 4, which is carried by the body portion 2. The detachable member is recessed, as indicated at 5, to receive a nut 6, and after this nut has been placed within the recess a plug 7 is driven 75 therein, whereby the recess will be closed and the nut prevented from becoming loose or 80 disengaged from this detachable member. Through this member I provide the apertures 8 in horizontal alignment with the apertures carried by the nuts, and adapted to pass through these apertures are the bolts 4, carrying upon their outer ends the washers 9 and the square shank portion 10, over which is adapted to be placed a suitable key or wrench, whereby these bolts may be readily rotated 85 to engage or become disengaged from the nut 6. In the body portion 2 of the sash I provide the annular recesses 11, in which are placed the cups 12, these cups having an aperture formed in their base, which is adapted 90 to register with an aperture 14, drilled in the body portion of the sash and registering with 95

the aperture 8, formed in the detachable member. On the opposite side of the sash I provide the socket members 15 of the hinge, and in the frame of the window I provide the recess 16 and slots 17 and 18 to receive the other member 19 of the hinge and the adjusting mechanism, which consists of a strip 20, having slots 21 formed therein, which slots extend diagonally across the strip, and adapt-

- 5 to engage in these slots are the stub-shafts 22, which are carried by the hinge members 19, that extend through the slots 17 of the frame. On the lower end of the strip 20 I provide a handle 28, which extends outwardly
- 10 at right angles to the strip, this handle being adapted to extend through the slot 18 of the frame and through the slot 29 of the plate 30.
- 15

When it is desired to remove the sash, a key or wrench is inserted within the cup 11 to engage over the square shank 10 of the bolt 4, and when the same is rotated it is disengaged from the nut 6 and may be readily removed, so the body portion of the sash may be swung from the frame. To accomplish this, the socket members 15 of the hinge are engaged over the members 19, as illustrated in Fig. 1 of the drawings, the window being slightly raised, whereby the same may be swung outwardly to clear the base strip of the frame. When it is desired to raise the window or close the same entirely, the handle 28 is pulled downwardly, whereby the stub-shafts 22 will be forced to the other side of the strip 20 through the medium of the slots 21, thus causing the hinge members 15 and 19 to move farther within the recess 16 and the slot 17, permitting the socket members 15 of the hinge to pass the members 19 when it is desired to close the window. It will of course be seen from Fig. 1 of the drawings that the sash of the window may be raised independently of the hinge members 19. It will be noted that I may readily employ any number of the locking-bolts upon the body portion of the sash in order that the detachable member may be firmly held in its place.

In Fig. 4 I have shown an angle-strip 2' at-

tached to the sash and in Fig. 5 have shown a short section 3' of an angle-strip attached to the removable portion of the sash-rail. 50 When this removable portion is in position on the sash, the section 3' alines with angle-strip 2', and the strip forms the shed member of the weather-strip, such as shown in my application filed January 6, 1904, Serial No. 55 187,928, and fully described therein.

In the practice of the invention it will be evident that various slight changes may be made in the details of construction without departing from the general spirit of the invention. 60

Having fully described my invention, what I claim as new, and desire to secure by Letters Patent, is—

1. In combination with a window-frame carrying hinge members, a sash having hinge members on one of its vertical rails to be engaged with the hinge members of the frame, a detachable member secured to the other vertical rail of the sash, and means comprising 70 nuts embedded in the detachable member, and bolts extending through the vertical rail and detachable member and taking into the said nuts to secure the detachable member in position.

2. In a window-sash having hinge members secured to one of its vertical rails, in combination with a frame, movable hinge members in the frame adapted to be engaged with the hinge members on the sash, a vertical strip 80 arranged in a recess provided therefor in the frame and having slots extending diagonally of the strip, shafts carried by the movable hinge members to engage in said slots, and a handle secured to the strip and projecting 85 outside the frame for operating the strip to actuate the movable hinge members, substantially as described.

In testimony whereof I affix my signature in the presence of two witnesses.

CHARLES M. RHODES.
